UNITED STATES PATENT OFFICE

LOUIS NITHSDALE FORSYTH, OF NEW IBERIA, LOUISIANA

DESIGN FOR AN ORNAMENT FOR AUTOMOBILE RADIATOR CAPS OR THE LIKE

Application filed September 11, 1930. Serial No. 36,941. Term of patent 3½ years.

To all whom it may concern:

Be it known that I, LOUIS NITHSDALE FORSYTH, a citizen of Guatemala, Central America, residing at New Iberia, in the parish of Iberia and State of Louisiana, have invented a new, original, and ornamental Design for an Ornament for Automobile Radiator Caps or the Like, of which the following is a specification, reference being had to the accompanying drawing, forming part thereof.

Figure 1 is a side elevation of an ornament

for automobile radiator caps or the like showing my new design.

Fig. 2 is a similar view taken from the opposite side of Fig. 1; and

Fig. 3 is a top plan view thereof.

I claim:

The ornamental design for an ornament for automobile radiator caps, or the like, as shown.

LOUIS NITHSDALE FORSYTH.
